(57) **CLAIM**

The ornament design for a design for an apparatus for depositing cell samples on microscope slide, as show and described.

DESCRIPTION

FIG. 1 is a front perspective view from a left side of an apparatus for depositing cell samples on microscope slide showing my design;

FIG. 2 is a front elevational view of the apparatus for depositing cell samples on microscope slide shown in FIG. 1;

FIG. 3 is a right side view thereof;

FIG. 4 is a left side view thereof;

FIG. 5 is a top plan view thereof; and

FIG. 6 is a bottom plan thereof; and,

FIG. 7 is a rear elevational view thereof.
